United States Patent Office.

JOHN B. SCHENCK, OF MATTEAWAN, NEW YORK.

Letters Patent No. 99,599, dated February 8, 1870.

IMPROVEMENT IN PLANING-MACHINE.

The Schedule referred to in these Letters Patent and making part of the same

To all whom it may concern:

Be it known that I, JOHN B. SCHENCK, of Matteawan, in the county of Dutchess, and State of New York, have invented a new and useful Improvement in Woodworth Planing-Machines; and I do hereby declare that the following is a full, clear, and exact description thereof, which will enable others skilled in the art to make and use the same, reference being had to the accompanying drawings, forming part of this specification.

This invention relates to a new and useful improvement in "Woodworth, or other planers," where slight adjustment are to be made; and

It consists in elevating and depressing the cutter-cylinder, by moving (longitudinally) a horizontal bar connected with the boxes of the outer cylinder-shaft, by oblique slides, whereby a vertical motion is obtained for adjusting the cutters.

It also consists in serrating the edges of the cutters or knives, for adapting them to cross-grain planing, as will be hereinafter more fully described.

In the accompanying plate of drawings—

Figure 1 represents a vertical section of the arrangement through the line *x x* of fig. 2.

Figure 2 is a vertical section looking to the right, from the line *y y* of fig. 1.

Similar letters of reference indicate corresponding parts.

A is the frame of the machine.

B represents the cutter-cylinder, with the cutters attached.

B' represents the cutters or knives.

C C represent the cylinder-shaft boxes.

D D represent vertical slides, to which the boxes are attached.

E E represent stationary hangers, suspended from the frame, and connected with the vertical slides D, by dovetail on the slides, and dovetail grooves in the hangers, so that the slides, with the cutters, have a free movement up and down.

F is a horizontal bar, passing between the hangers and the slides D, with obliquely-placed slides, G G, upon its side, as seen in the drawing, which work in oblique grooves in the vertical slides D, as indicated in dotted lines in the drawing.

H is a crank-screw, which is connected with the bar F by the lug-nut I.

The screw H is supported from the frame, as seen at J.

It will be seen, that by turning the screw H in either direction, the bar F is forced one way or the other, whereby the shaft and cutters will be raised or lowered

by virtue of the oblique slides G, sliding in the inclined grooves in the upright D, and the adjustment made in the most complete manner. When the adjustment is thus made, the slides are secured in place by the standing bolts and nuts K K, which project through the slots L L, as seen in the drawing.

For planing lumber across the grain for certain uses, I groove or serrate the faces or edges of the knives in such manner, as that when the cutter-cylinder revolves, the grooves or serrations in the knives or cutters will not follow each other, but the grooves or serrations will vary, so that the wood left uncut by one knife or cutter, will be cut clean by the next succeeding knife or cutter, and at each revolution of the cutter-cylinder the cutting-edges between the grooves or serrations will have smoothed the entire surface of the wood being planed, and in this way prevent the wide shavings from clogging the cutter, or tearing the grain of the wood.

In planing stuff with a full-edged or plane knife, a shaving is cut the full width of the piece of lumber, making a long straw-like chip or shaving, which clogs the machine, and occasions much trouble and delay, as the draught produced by the revolving cylinder will not throw them out.

By the use of the serrated knives, the shavings are cut in short pieces, and the draught keeps them clear of the cutters.

Having thus described my invention,

I claim as new, and desire to secure by Letters Patent—

1. The combination of the crank-screw H, support J, nut I, with the bar F, slides G G, sliding in oblique grooves in uprights D, and in horizontal slots in hangers E E, cylinder-axle boxes C C, and cylinder B, all constructed and arranged to operate in the manner and for the purpose described.

2. The combination of the devices above claimed, with the retaining-bolts and nuts K K, in slots L L, of the supports of the axle boxes C C, in the manner and for the purpose described.

3. The cylinder B, provided with knives or cutters B', having grooves or serrations in their cutting-edges, when said grooves or serrations are placed in the several knives, in the manner and for the purpose described.

The above specification of my invention signed by me, this 1st day of March, 1869.

JOHN B. SCHENCK.
